DRAFT MECHANISM FOR RAILWAY CARS

Argyle Campbell, Chicago, Ill., assignor to Enterprise Railway Equipment Company, Chicago, Ill., a corporation of Illinois

Application March 27, 1943, Serial No. 480,738

7 Claims. (Cl. 213—32)

1

My invention relates to improvements in draft mechanism for railway cars.

One of the objects of the invention is to improve the efficiency of the draft mechanism in its ability to respond to the shocks of buff and draft action by providing improved support and guidance for the draft gear at front and rear ends so that the yoke and draft gear will move as a unit and in proper alignment.

A further object is the provision of a floating unit including the yoke or beam and draft gear arranged for better cushioning of the rebound of the draft gear when subjected to severe shocks in buffing or pulling the car, and particularly for better absorption of the "jolt" and "jerk" shocks delivered to the draft mechanism of a train of cars hard to start by the engineer in causing the engine to first hit and then quickly reverse and jerk the train.

Another object is to provide a unitary structure in which the shock absorbing mechanism for buffing shocks is separate from and independent of the shock absorbing mechanism for draft shocks, so that each functions independently of the other.

Other objects of the invention will appear from the description and the combination and arrangements of parts shown in the accompanying drawings which illustrate one embodiment of the invention, and in which

Fig. 1 is a plan section of a draft gear mechanism in relation to the center sills and coupler of a railway car and illustrating the unitary structure including the floating yoke and independently acting shock absorbing mechanism;

Fig. 2 is a view in side elevation of the draft mechanism unit shown in Fig. 1, the center sills and supporting keys being shown in section;

Fig. 3 is a plan view of the improved floating beam member;

Fig. 4 is a view in side elevation of said beam member;

Fig. 5 is a detail transverse section on line 5—5 of Fig. 2; and

Fig. 6 is a detail transverse section on line 6—6 of Fig. 4.

In Figs. 1 and 2, the usual center sill members A are shown spaced apart and extending lengthwise of the car. Inwardly of the forward ends of the center sill is shown the usual center filler 1 and bolster 2, and projecting from the forward or front end of the center sills is a coupler 3 of standard construction having a shank or butt 4 which is connected to and by

2

which the buffing and draft shocks are transmitted to the draft mechanism.

Within the center sills are provided the usual forward and rear draft or stop lugs 5 and 6 respectively, and bearing against these stops are the forward and rear follower plates 7 and 8 respectively. The draft mechanism is located within the spaced center sills and the shock absorbing mechanisms which form a part of the unit are carried by the yoke or beam B and are located lengthwise between the two follower plates 7 and 8.

The yoke or beam B is preferably cast or formed as a one-piece integral structure and comprises longitudinal parallelly disposed top and bottom members 9 and 10 respectively, which are connected at their end portions by the vertical walls 11—12 which form the yoke ends and which are spaced apart laterally to bring them relatively close to the vertical walls of the center sills but with sufficient clearance, however, to permit the beam to move freely longitudinally. At the forward end, the shank of the coupler extends in between these yoke end walls and is provided with a transverse or horizontal key 13 which is inserted through a suitable slot 14 in the shank. This key extends through registering slots in the yoke end walls and when in place locks the beam or yoke to the coupler so that the beam moves longitudinally in both directions with the coupler. The key likewise extends through registering slots 15 in the vertical walls of the center sills and thus supports and guides the coupler and the forward end of the beam. The slots 15 are elongated sufficiently to allow for the longitudinal movement of the beam in both directions in response to the corresponding movement of the coupler.

In like manner, the rear yoke end walls 12 are slotted to receive a transverse key 16 which moves with the yoke but which extends through registering slots 17 in the side walls of the sills to support and guide the rear end of the yoke beam. These guide slots 17 are elongated sufficiently to correspond to the longitudinal movement of the yoke beam in either direction. It will thus be seen that the beam, and all the parts carried thereby, is supported and guided at both ends in such manner that it constitutes a floating unit capable of longitudinal movement in both directions in response to the coupler movements.

As before mentioned, the shock absorbing gear is positioned within and carried by the beam and is located between the two follower plates 7

and 8. In the present structure, I provide two shock absorbing units C and D which, although integral with the yoke or beam, function independently of each other in response to the buffing and pulling shocks. These shock absorbing units comprise cylindrical shell portions 18 which are formed integrally with the beam members 9 and 10, and which contain the tapered friction shoes 19 and the cooperating friction wedges 20 which bear against the follower plates 7 and 8. The friction elements are assembled within the shells by the bolts 21, together with the followers 22 and the springs 23, so that each friction shock absorbing unit can act independently of the other. The intermediate portion 24 of the beam is made integral with and wider than the top and bottom members 9 and 10, and is made preferably rectangular in section, as shown in Fig. 6, to provide space for a nest of springs 25 which, at their ends, bear against the followers 22 of the shock absorbing units so that although the shock absorbing units function independently of each other they both are assisted by a common set of springs 25. The side or vertical walls 26 of the spring housing are provided with windows or openings 27 to permit the insertion of the springs 25 in assembling the mechanism. At the rear of the beam, the inner ends 28 of the yoke end walls 12 bear against the rear follower plate 8.

It will thus be seen that the entire draft mechanism forms, in a sense, an oscillating unit in response to the movements of the coupler. When the coupler receives a buffing shock, the butt of the shank bears against the follower plate 7; but since the beam is locked to the coupler by the key 13, this buffing shock is transmitted to the beam and the beam moves rearwardly with the coupler. No relative movement occurs between the friction elements of shock absorbing unit C, and hence this unit does not function on the occasion of buffing shocks. The rear shock unit D, however, bears against the follower plate 8, and the shell thereof moves with the yoke and compresses the friction elements to absorb the buffing shock. The rear yoke ends 28 on this occasion move rearwardly away from the follower plate.

On the occurrence of a pulling or draft shock, however, the yoke is moved forward with the coupler and carries the follower plate 8 and the shock absorbing unit with it, so that there is no relative movement between the shock absorbing unit D and the follower plate 8. However, the shock absorbing unit C moves forward with the yoke compresses its friction elements against the forward follower plate 7 which is against the stops 5. Thus, on the draft or pulling shocks, the forward shock absorbing unit C functions to absorb this shock. Since there are two independent shock absorbing units, each one functions a lesser number of times than if a single shock absorbing unit were employed, as is the case with standard draft gear. The wear on the friction elements, therefore, is very much reduced and replacements made less frequent.

I claim:

1. In a railway car having center sills, the combination of a longitudinally movable yoke member positioned between the center sills, shock cushioning devices positioned within the yoke, front and rear draft lugs fixedly attached to the inner sides of the center sills, the said movable yoke member having at both its front and rear ends slots for the passage of transverse key bars,

a front key bar for passage through said front slots, a slot of similar size in the coupler shank and through elongated slots in said center sills which permit forward and rearward movement of the key bar, a rear key bar for passage through said rear slot in the yoke member and through elongated slots in the center sills which extend forwardly and rearwardly to permit movement in both directions of the key bar, whereby the weight of the movable yoke, shock cushioning devices and key bars is supported at both its front and rear ends by the walls of the center sills, and the slots in the center sills guide and confine their movement in longitudinal alignment.

2. In a draft mechanism for railway cars, the combination of the center sills of a car, draft mechanism positioned within said center sills, a coupler at the forward end of said draft mechanism connected to said beam and adapted to move the beam longitudinally in either direction, forward and rear stops within said center sills, said draft mechanism comprising a hollow beam, transverse keys extending through the ends of said beam and mounted in guide slots in the center sill walls for supporting and guiding the beam in longitudinal movement in both directions, the slots in the centersills being extended to permit movement of the keys in both directions from normal and independent shock absorbing units carried within said beam and comprising housings integral with said beam and friction shoes movable in said housings and bearing against said stops.

3. In a draft mechanism for railway cars, the combination of car centersills spaced apart and having forward and rear draft lugs on their inner faces, follower plates bearing against said stops, a shock absorbing unit bearing against the forward follower plate and responsive only to draft shocks, an independent shock absorbing unit bearing against said rear follower plate and responsive only to buffing shocks, a yoke member positioned between the centersills forming a common carrier for both of said shock absorbing units, and movable upon a draft shock to force the forward unit against said forward follower plate and upon a buff shock to force the independent unit against said rear follower plate, and a coupler connected to the forward end of the yoke to move the yoke longitudinally itself in both directions.

4. In a draft mechanism for railway cars, the combination of car centersills spaced apart and having forward and rear draft lugs on their inner faces, follower plates bearing against said stops, a friction shock absorbing unit bearing against the forward follower plate, an independent friction shock absorbing unit bearing against said rear follower plate, a spring cushioning device between and common to both friction units, a yoke member positioned between the centersills forming a common carrier for said shock absorbing units and spring cushioning device, and movable upon a draft shock to force the forward unit against said forward follower plate and upon a buff shock to force the independent unit against said rear follower plate, a transverse key at each end of said yoke extending through elongated longitudinal slots in said centersills for supporting and guiding the yoke, said elongated slots being extended to permit movement of the keys in both directions from normal, and a coupler connected to the forward end of the yoke by the transverse key to move the yoke longitudinally of itself.

5. In a draft mechanism for railway cars, the combination of a pair of spaced car centersills, a yoke member positioned between the centersills and having integral forward and rear shock absorbing unit housings arranged in alignment, a spring pocket integral with the yoke intermediate said housings, spring means in said pocket common to both shock absorbing units, each shock absorbing unit housing having friction wedge members at one end, forward and rear draft lugs and follower plates in said centersills acting independently on the friction members of said units in accordance with the direction of movement of the yoke, a coupler connected with the forward end of yoke to move the yoke longitudinally in either direction, and means at both ends of the yoke engaging elongated slots in the center sill walls for supporting and guiding the yoke.

6. In a draft mechanism for railway cars, the combination of car centersills spaced apart and having forward and rear draft lugs on their inner faces, follower plates bearing against said stops, a yoke member positioned between said centersills and supported by said centersills for movement in both directions, a coupler connected with the forward end of said yoke member for moving the yoke member in both directions in response to draft and buff forces applied thereto, shock absorbing units carried entirely by said yoke member and each comprising a shell portion integral with and movable by said yoke and friction members in

tion members in said shells bearing against said follower plates, an intermediate spring shock absorbing means carried by said yoke member common to both shock absorbing units and positioned therebetween, and means for rendering either one of said shock absorbing units effective depending upon the direction of movement of said yoke member.

7. In a draft mechanism for railway cars, the combination of car centersills spaced apart and having forward and rear draft lugs on their inner faces, follower plates bearing against said stops, a yoke member positioned between said centersills and supported by said centersills for movement in both directions, a coupler connected with the forward end of said yoke member for moving the yoke member in both direction in response to draft and buff forces applied thereto, shock absorbing units carried entirely by said yoke member and each comprising a shell portion integral with and movable by said yoke and friction members in said shells bearing against said follower plates, an intermediate spring shock absorbing means carried by said yoke member common to both shock absorbing units and positioned therebetween, and intermediate stops on said centersills for rendering either one of said shock absorbing units ineffective depending upon the direction of movement of the yoke member.

ARGYLE CAMPBELL.
